[57] **CLAIM**

The ornamental design for a pinhole headlamp video camera, for medical and surgical applications, as shown.

DESCRIPTION

FIG. 1 is a perspective view of the pinhole headlamp video camera for medical and surgical applications.

FIG. 2 is a side view of the pinhole headlamp video camera the other side being a mirror image;

FIG. 3 is a front view of the pinhole headlamp video camera; FIG. 4 is a back view of the pinhole headlamp video camera; FIG. 5 is a bottom view of the pinhole headlamp video camera; and,

FIG. 6 is a top view of the pinhole headlamp video camera. The truncation of the camera source piping in the FIG. 1-4 indicates indeterminate length.
